UNITED STATES PATENT OFFICE.

JOHN A. LAMONT, OF GRANITE CITY, ILLINOIS, ASSIGNOR TO AMERICAN STEEL
FOUNDRIES, OF NEW YORK, N. Y., A CORPORATION OF NEW JERSEY.

CAR-TRUCK SIDE FRAME.

1,157,876.

Specification of Letters Patent.

Patented Oct. 26, 1915.

Application filed April 22, 1915. Serial No. 23,031.

To all whom it may concern:

Be it known that I, JOHN A. LAMONT, a citizen of the United States, and resident of Granite City, in the county of Madison and State of Illinois, have invented certain new and useful Improvements in Car-Truck Side Frames, of which the following is a specification.

My invention relates to railway cars, and has particular reference to a novel built-up side frame for use in connection with car trucks.

An object in the construction of the present device is to provide for economy in cost of construction. This economy is the result of the use of commercial rolled sections which are fabricated to form a substantially integral side frame structure.

A further object is to lessen the weight of such structures by so disposing the metal thereof that the greatest possible resistance is secured with minimum weight. In the present structure the principal parts of the truss, namely—the compression and tension members, are formed from commercial rolled shapes, the remainder of the parts being formed by casting in steel or malleable iron.

The invention will be more readily understood by reference to the accompanying drawings, wherein—

Figure 1 is a side elevation of a portion of a side frame constructed in accordance with my invention, Fig. 2 is a fragmentary elevation of a slightly modified form, Fig. 3 shows a still further modification, and Fig. 4 is a plan view of the construction shown in Fig. 3 with the compression member removed.

In the drawings, the compression member 10 is indicated as formed from a rolled channel, the flanges of the channel in Fig. 1 being sheared off at 11 to lie against an inclined shoulder 12 formed on a casting 13, which serves to secure the ends of the truss. Between the two flanges or shoulders 12, which serve as a bearing for the flanges of the channel, I provide a recess within which a portion 14 of the web of the channel is accommodated. This portion of the web is bent upward into line with the tension member, and the end 15 of the web is bent back upon itself to increase the thickness at that point. The tension member is of T-shape, having a flange 16 and a web 17. The flange 55 is sheared off at the point 18, the web con-

tinuing and its end 19 being bent around the end 15 of the compression member. Thus it will be seen that the tension member continues straight from the strut to the bearing end of the member. A rivet 20 is passed through the tension and compression members and casting. The casting 13 is provided with a recess, so shaped as to properly fit the tension member, and above the tension member, at a point adjacent to the junction of the tension and compression members, I provide an extension 21 of the casting which lies against the web of the compression member and is secured thereto by suitable rivets 22. The casting is likewise provided with jaws 23, between which a journal-box may be accommodated, although it will be understood that I may prefer to form the journal-box integral with the casting. The strut for the truss comprises two columns 24 which serve as bolster guides.

In the construction of Fig. 2, the compression member 25 is likewise of channel form, its flanges abutting against a shoulder 26 formed on a casting 27. The web 28 of the channel continues beyond the end of the flanges. The tension member in this instance is shown as of rolled channel form, the flanges 29 thereof being sheared off, as indicated by the dotted line 30, the web 31 being bent into the plane of the web of the channel, as indicated at 32, thence bent or hooked around the end of the web of the compression member, as indicated at 33. The casting 27 is otherwise much of the same form as that shown in Fig. 1, jaws 34 being provided within which the journal-box is accommodated. The use of the channel section as a tension member facilitates the use of rivets 35 for attaching the flanges of the member to the casting.

In Fig. 3 the construction is quite similar to that shown in Fig. 2, except that the compression member 36 is cut off square at its ends and abuts against the shoulder 37 on the casting 38. The tension member is likewise of channel section, and its web 39 is bent into the plane of the compression member, its end 40 being bent up against but not around the compression member. In order to secure proper holding engagement, I may provide the rivet 41 for securing the three elements together.

The construction shown provides for the theoretically correct disposition of metal to

best resist strains. The use of economical rolled or pressed sections for the main members of the truss and the use of a steel casting for the portion of the frame requiring rigidity results in a structure which is not readily broken, is light in weight and very economical in first cost.

It will be understood that wherever I have referred to the use of rolled shapes that 10 pressed shapes might be used with equal facility and that therefore I consider the terms rolled and pressed as synonymous.

I claim:

1. In a side frame, the combination of a 15 compression member of channel shape and a tension member of T shape, the ends of said members being brought into engagement, the vertical web of the T being sheared off at the ends of the compression member, the web of the tension member being bent upward to form an abutment for the end of the compression member, and a pedestal casting with which said members coöperate

at their ends, the tension member being fitted into an opening through said casting, substantially as described. 25

2. In a side frame, the combination of a channel-shaped compression member, and a T-shaped tension member, a pedestal casting uniting the members at their ends, said casting being provided with a diagonal aperture for the accommodation of the tension member, the web of the tension member being sheared off at the end to permit the same to lie against the compression member, the extreme end of the tension member being bent up to form an abutment for the compression member, the web of the compression member being united to a web of said casting, substantially as described. 30 35 40

Signed at Granite City, Illinois, this 7 day of April, 1915.

JOHN A. LAMONT.
